UNITED STATES PATENT OFFICE.

GEOERGE WOODSON CROWE, OF SANTA CRUZ, CALIFORNIA.

ORE DISINTEGRATING AND SCREENING MACHINE.

1,156,394.

Specification of Letters Patent.

Patented Oct. 12, 1915.

Application filed September 16, 1913. Serial No. 790,052.

To all whom it may concern:

Be it known that I, GEORGE WOODSON CROWE, a citizen of the United States, residing at Santa Cruz, in the county of Santa Cruz and State of California, have invented certain new and useful Improvements in Ore Disintegrating and Screening Machines, of which the following is a specification.

This invention relates to improvements in apparatus for treating auriferous gravel or other ore-bearing material to disintegrate and screen the same prior to its subjection to quicksilver in the sluice-box riffles. The apparatus being particularly desirable for working ore-bearing material that could not be easily subjected to the sluicing operations and which is consolidated by cement so that disintegration by attrition and erosion is necessary.

One of the objects of the invention is to provide a unitary rotatable shell-structure wherein the material in its passage therethrough is first subjected to disintegrating action and subsequently to a separating, classifying, and screening action whereby boulders or larger pieces of material will be separated from the finer pieces.

A further object is to provide a disintegrating portion which will not only act to cause disintegration by the mass rolling upon itself, but which will advance the mass during such disintegration.

A still further object is to control the passage of the mass, relatively to its rate of speed, by the relative size of the inlet with respect to the outlet, by the spiral setting of the disintegrating members, by the inclination of the apparatus and amount of water supply and also by speed of rotation.

Other objects and features of the invention consist in the construction relative to the anchorage of disintegrating members and wearing plates, employed in a disintegrating section, and the construction and arrangement of the parts employed in the screening section.

Other features of novelty will be more fully described in connection with the accompanying drawings and will be more particularly pointed out in and by the appended claims.

In the drawings, Figure 1 is an end view looking toward the discharge end of the ap-

paratus. Fig. 2 is a longitudinal sectional view. Fig. 3 is a transverse sectional view on line 3—3 of Fig. 2. Fig. 4 is a transverse sectional view on line 4—4 of Fig. 2.

As illustrated, I have shown the device of my invention in the form of a cylindrical shell 1 which is provided with an imperforate portion 2 and a perforate portion 3. A feed head 4 is provided with a feed opening 5 whereby ore may be fed therethrough by a chute or other suitable means not shown. The discharge head 6 is provided with a discharge opening 7 which is relatively enlarged with respect to the size of the feed opening 5. The feed and discharge heads may be proportioned with respect to their openings so as to, in a measure, govern the speed or rate of passage of the material through the apparatus.

Peripherally of the shell 1 mount rails 8, 9 and 10 adapted to run on and be supported by sets of flange wheels 11, 12 and 13, respectively, which wheels are shown mounted upon a supporting frame. The supporting frame consists of transversely disposed pairs of frame members 14, 15 and 16 upon which the supporting wheels 80 are mounted, bearings 17, 18 and 19 being provided in which suitable shafts for the wheels may be journaled. Said frame may also comprise longitudinal frame members 20 and 21 suitably tied by rods 22. An operating shaft 23 is journaled in bearings 24 and 25 and is provided with pinions 26 adapted to mesh with circular racks 27, which latter are suitably mounted upon the imperforate portion 2 of the shell 1.

It will be readily seen from the foregoing that the shell may be rotated at any desired speed about its longitudinal axis.

A lining is provided for the imperforate portion 2 of the shell and said lining, as shown, consists of a plurality of wearing plates which may be in the form of segments or sections 28 having their adjacent sides 29 disposed in relatively close relation and being employed in such proportions and such numbers as to substantially completely line the imperforate portion 2. The abutting ends 30 of the plates 28 preferably meet in staggered relation, the plates being disposed in parallel rings with the circumferential spaced joints staggered a sufficient

distance to permit the same to be covered by disintegrating parts which will now be described.

I find it convenient to use railroad rails as 5 disintegrating bars for carrying the material upwardly and cause the resulting descending movement of the material to effect disintegrating action by attrition upon itself and also upon the disintegrating members. 10 One of the rails is indicated at 31, in Fig. 2, and is shown to be straight in form but disposed at an angle or slightly canted with respect to the longitudinal axis of the shell 1. The inclined disposition of the rail or rails 15 is such as to provide a spiral disposition such as will advance the material toward the discharge end 7, the direction of rotation being indicated by the arrow in Fig. 2.

I preferably anchor the rails 31 by means 20 having adjustable tightening portions exposed exteriorly of the shell for ready access for purposes of adjustment and also to protect such portions from injurious action to which they would be subjected if they 25 were interiorly disposed.

As shown, U-shaped bolts 32 are disposed through suitable openings provided in the webs of the rails 31, the flanges of the rails being slotted, as shown at 33, so that the bolts will not only hold the rails against the lining of the shell but also lock the same against circumferential displacement. At the meeting ends of the lining plates 28 I provide slots 34 for passage therethrough of 30 the ends of the bolts 32. The imperforate portion 2 of the shell is provided with openings for projection therethrough of the threaded ends of the bolts so that nuts 35 can be applied to tighten the bolts. Intermediate of the ends of the plates 28 I provide slots 36 for passage of those rails intermediate the end plate-covering rails.

It will be seen by reference to Fig. 2, that 45 the rail 31 covers the joints of the adjacent end plates and that the latter are arranged to break joint in such a manner that the flange of the rail will cover all of the joints. It will be seen from the foregoing that the bolts not only function to hold the rails against displacement in any direction with respect to the shell but they likewise hold the lining plates. The perforate end 3 is provided with a perforate or screening portion which may comprise a plurality of 50 openings 37 disposed in the shell 1. Abreast of the outermost openings I preferably provide guards which may be in the form of angle-rings 38, suitably secured to the shell 1. These guards 38 inwardly overlap the entrance sides 39 of a discharge chute 40 and I carry the entrance sides 39 upwardly about the screening portion 3, as shown in Fig. 4.

The screening portion 3 is lined with a plurality of bars 41 which are shown dis-

posed longitudinally of the axis of the shell 65 and parallel with such axis. The bars 41 preferably extend lengthwise of the shell beyond the perforated portion and nearest the disintegrating portion 2, I provide a shield or deflector 42 which overhangs the inner 70 ends of the bars 41. Said deflector or shield may be in the form of a Z-iron or ring having a flange 43 secured to the shell 1. The bars 41, as shown more particularly in Fig. 4, are tapered transversely and are disposed with their larger edges radially innermost and their smaller edges radially outermost. Suitable spacing blocks 44 are interposed between the bars 41 to distance the same in suitable spaced relation. If it is desired to 80 tie a plurality of bars together in a section, by bolts 45, the same may be put in and removed in sections, one or more bars being independent to provide keys to permit of removal or insertion of the remaining bars 85 in sections. The bars are anchored against endwise movement, and preferably in abutting relation against the shield 42 by a filling ring 46 which may be formed in sections, which are interposed between the outer ends 90 of the bars 41 and the head 6. The outer ends of the bars 41 are prevented from movement radially inwardly by a retaining ring 47 which may be in the form of sections and which is shown anchored to the 95 shell 1 by bolt 48, by bolts which may pass through the filling ring sections 46.

Means may be provided for supplying water under pressure so as to effect corrosion during disintegration, and as shown, said 100 means consists of a pipe 49 which may be extended through the shell as shown and connected with any suitable source of supply of water under pressure. That end of the pipe adjacent the feed head 4 may be supported by a bracket 50. I have shown the pipe 49 provided with perforations 51 extending throughout the length of the pipe but in most cases the supply of water will only be necessary in a disintegrating portion 2. In cases where a dry operation is possible the pipe may be dispensed with.

In operation, disintegration results from action between the material and the bars 31, the latter serving to carry up the material 115 in the direction of rotation of the shell and then releasing material so that it falls upon itself and is subjected to a grinding and disintegrating action causing a reduction of the material into a mass composed of large and small-sized pieces. On this rolling mass the water under pressure is projected and a corrosive as well as a disintegrating action will result. Longitudinally, the surface of the material will slope from the inlet to the 125 discharge end, the slope being more pronounced near the discharge end by reason of egress of the finer material through the

perforate portion of the shell, the larger pieces of material being ejected through the opening 7 of the discharge head 6.

It will be seen that three methods of disintegration are possible with the device of my invention, namely, attrition of the gravel and boulders on the bars or rails 31, attrition and grinding of the boulders and gravel when one portion of the mass descends upon another, and disintegration and erosion by jets of water under pressure applied to the moving mass. It will also be noted that in one shell I combine a disintegrating and classifying device, the disposition and storing of the classified material being entirely by water.

It is believed that the advantages of the invention will be fully understood from the foregoing description, and while I have herein shown and described one specific form of the invention, I do not wish to be limited thereto except for such limitations as the claims may import.

I claim:

1. In an ore reducer, a rotary shell, a lining for said shell composed of wearing plates disposed in circumferential rings about the interior of said shell and arranged with the junctures of the plates of one ring circumferentially and successively advanced with respect to the junctures of the plates of the next adjacent ring throughout the length of the lining, and disintegrating bars disposed along said plates and covering the junctures of the plates abreast of which the bar is disposed.

2. In an ore reducer, a rotary shell, a lining for said shell composed of wearing plates disposed in circumferential rings about the interior of said shell with the meeting junctures of the plates of the successive rings being circumferentially advanced with respect to the first ring in one direction longitudinally of the shell, and a disintegrating member disposed longitudinally of the shell and covering the junctures of the plates along which it is mounted.

3. In an ore reducer, a rotary shell, a lining for said shell composed of wearing plates arranged to break joints, and a disintegrating element disposed on said plates in a position to cover the joints between the same.

4. In an ore reducer, a rotary shell, a lining for said shell composed of wearing plates having end meeting margins disposed parallel with the longitudinal axis of said shell and the plates being arranged so that the joints between adjacent sets of plates will be out of alinement, and means positioned over said joints and secured against the plates to cover the joints thereof.

5. In an ore reducer, a rotary shell, a lining for said shell composed of wearing plates disposed in circumferential rings with the

meeting ends of said plates disposed in parallel relation with the longitudinal axis of said shell and the plates of one ring being disposed to lock their meeting ends out of alinement with respect to the plates of another ring, and a disintegrating bar disposed on said plates and locked to cover said meeting ends.

6. In an ore reducer, a rotary shell, a lining for said shell composed of a plurality of wearing plates, a disintegrating bar disposed on said shell and consisting of a length of railroad rail having openings in its web, and recesses in its flanges, U-shaped bolts extending through the openings and recesses in said rail and through said shell, and means engaging the ends of said bolts and shell exteriorly of the latter for tightening said bolts.

7. In an ore reducer, a rotary shell, a lining for said shell comprising a plurality of wearing plates having slotted portions therein, a railroad rail mounted on said plates and having openings in its web and recesses in its flanges, U-shaped bolts extending through the openings and recesses in said rail and through the slotted portions of said plates exteriorly of the shell, and means exteriorly of the shell for tightening said bolts.

8. In an ore reducer, a rotary shell, a lining for said shell comprising a plurality of plates having meeting margins provided with slots therein, a railroad rail covering the meeting margins of said plates and provided with openings in its web and in its flanges, U-shaped bolts extending through said openings and recesses in the rail and through the slots of said meeting margins outwardly through said shell, and means exteriorly of said shell for tightening said bolts.

9. In an ore reducer, a rotary shell, a lining for said shell comprising a plurality of wearing plates arranged to extend around the inner circumferential walls thereof, a plurality of like rings also consisting of wearing plates fitted together, arranged in end abutting relation with said first ring and fixed to have the joints between the plates thereof offset, and means arranged to extend across the joints between the plates of the several members in the offset relation to form a longitudinal and spirally advanced disintegrating member.

10. In an ore reducer, a rotary shell, a lining ring for said shell comprising a plurality of wearing plates arranged to extend around the inner circumferential walls thereof, a plurality of like rings also consisting of wearing plates fitted together and arranged in end abutting relation with said first ring and fixed to have the joints between the plates thereof offset, a plurality

of disintegrating members arranged within the shell and wearing plates to extend in a transverse relation across the joints between the plates of the various rings in an elongated spiral, and means to hold said disintegrating members in the operative relation and in a position to be engaged by the material as the shell is rotated.

11. In an ore reducer, a rotary shell comprising feed end disintegrating means and discharge end screening means, a plurality of wearing plates arranged in the disintegrating portion of said shell in edge-abutting relation to form a lining for inner circumferential wall thereof, disintegrating members mounted over said wearing plates to cover the abutting edges thereof and to extend in an advancing relation over the inner wall of the wearing plate to cause the material to be carried from the feed end to the screening means upon rotation of the

shell, and means to transmit a rotary motion to said shell.

12. In an ore reducer, a rotary shell provided with an intake disintegrating portion and a discharge screening portion, a plurality of wearing plates arranged in circumferential rings around said disintegrating portion to have the abutting edges thereof in offset relation, means by which rotary motion is given to the shell, and disintegrating members mounted upon the inner face of said wearing plates and over the abutting edges thereof to form baffles to direct the material from the disintegrating portion to the screening portion of the shell.

In testimony whereof I affix my signature in presence of two witnesses.

GEORGE WOODSON CROWE.

Witnesses:
